UNITED STATES PATENT OFFICE.

EDWARD B. TOWLE, OF NEWBURYPORT, ASSIGNOR TO THE JOHN RUSSELL CUTLERY COMPANY, OF TURNER'S FALLS, MASSACHUSETTS.

DESIGN FOR A SPOON OR ANALOGOUS ARTICLE.

SPECIFICATION forming part of Design No. 15,420, dated September 16, 1884.

Application filed June 21, 1884. Term of patent 7 years.

To all whom it may concern:

Be it known that I, EDWARD B. TOWLE, a citizen of the United States, residing at Newburyport, in the county of Essex and State of Massachusetts, have invented and produced a new and original Design for a Handle for a Spoon or Analogous Article, of which the following is a specification, reference being had to the accompanying photograph, forming a part thereof.

The photograph shows a plan view of a spoon having my newly-designed handle, said view being sufficient to fully illustrate my design, which consists in the ornamentation on the upper or more exposed surface of the handle.

That part of the surface of the handle, shaped as shown, at the outer end thereof, has thereon a "shield," A, which consists of a plane oval surface surrounded by a molding. On the shield near the outer end is a spray of flowers, a. On a space, B, of that part of the surface of the handle adjoining the shield are sprays of flowers or flower-work. The shank or smaller

part C has thereon two longitudinal rows, b b, 25 of raised facets, and between them a line, c, of bead-work. A molding, d, in transverse lines separates the space B from the portion C.

The leading features of my design are the oval shield, the flower-work on the space B, 30 and the facets and bead-work on the shank.

A handle having my design is suitable not only for a spoon, but also for an analogous article—such as a knife or fork.

I claim—

The design for the handle of a spoon or analogous article, having the configuration and ornamentation shown and described, the same consisting of the oval shield at the outer end of the handle, having the spray of flowers near 40 the outer end thereof, the flower-work on the space B, and the facets and bead-work on the shank C.

EDWARD B. TOWLE.
